UNITED STATES PATENT OFFICE.

EDWARD F. WHITE, OF QUINCY, MASSACHUSETTS, ASSIGNOR, BY DIRECT AND MESNE ASSIGNMENTS, TO CHARLES F. BROWN, TRUSTEE, OF READING, MASSACHUSETTS.

DESIGN FOR A SEAM-RUBBING TOOL.

SPECIFICATION forming part of Design No. 29,766, dated December 6, 1898.

Application filed November 12, 1898. Serial No. 696,299. Term of patent 14 years.

To all whom it may concern:

Be it known that I, EDWARD F. WHITE, of Quincy, in the county of Norfolk and State of Massachusetts, have invented and produced a certain new and original Design for 5 a Seam-Rubbing Tool, of which the following is a specification, reference being had to the accompanying drawings, forming a part thereof.

10 Of the drawings, Figure 1 represents a longitudinal sectional view of a seam-rubbing tool shaped in accordance with my design. Fig. 2 represents a front end elevation thereof. Fig. 3 represents a rear end elevation.

15 The tool is of the kind used in rubbing the welt-seams of shoes. It comprises a hollow shank or stem *a*, at the forward end of which is a head composed of a number of radiating teeth or projections *b b* of distinctive shape 20 or conformation. The front sides 2 2 of these teeth are substantially perpendicular to the

central axis of the tool, giving a substantially flat front face or side to the tool, while the back sides or edges 3 3 of said teeth are inclined or sloping with respect to the front 25 sides 2, meeting these sides at 4 4 to form comparatively sharp crests or edges. Down the back of each tooth or projection *b* is a ridge 5, whose face is the rear side 3 of the tooth. These ridges, which constitute the 30 rubbing-surface of the tool, have their edges rounded off.

I claim—

The design for a seam-rubbing tool, substantially as herein shown and described. 35

In testimony whereof I have affixed my signature in presence of two witnesses.

EDWARD F. WHITE.
